D. BARTOLACELLI

PADLOCK

Inventor
Delindo Bartolacelli

By J. E. Trabucco, Attorney.

UNITED STATES PATENT OFFICE.

DELINDO BARTOLACELLI, OF DALY CITY, CALIFORNIA.

PADLOCK.

Application filed May 2, 1922. Serial No. 557,843.

To all whom it may concern:

Be it known that I, DELINDO BARTOLACELLI, a subject of the King of Italy, residing at Daly City, in the county of San Mateo and State of California, have invented new and useful Improvements in Padlocks, of which the following is a specification.

This invention relates to a padlock and 10 has for its primary object to provide an improved construction, combination and arrangement of parts in a device of this character whereby the same may be securely held in a locked position until released by 15 the particular key fitting it.

Another object of this invention is to provide an improved means which permits the locking of the padlock without the insertion of the key therein, thereby preventing it 20 from being unlocked with any device other than the particular key made to fit the parts thereof.

Other and further objects, including, certain features of construction will appear in 25 the specification and be pointed out in the appended claim, reference being had to the accompanying drawings which show the preferred embodiments of my invention and in which—

30 Fig. 1 is a side elevation of the padlock showing the same in a locked position;

Fig. 2 is a side elevation of the key for the padlock;

Fig. 3 is a sectional view of the key in an 35 operative position;

Fig. 4 is an edge view of the key;

Fig. 5 is a detail sectional view of the 40 padlock taken on the line 5—6 of Fig. 8 showing the same in a locked position with one of its sides removed;

Fig. 6 is a view similar to Fig. 5 taken on the line 5—6 of Fig. 8 showing the padlock in an unlocked position with one of its sides removed;

45 Fig. 7 is a vertical cross section on the line 7—7 of Fig. 6;

Fig. 8 is a transverse section on the line 8—8 of Fig. 6;

Fig. 9 is a vertical transverse section on 50 line 9—9 of Fig. 6.

In the embodiment of my invention shown on the drawings, the main structure consists of a casing 1, into which the working parts of the lock are embodied, and into 55 two round holes 3, provided in the top thereof, the ends of the securing bow 2 are in-

serted. One end of securing bow 2 extends through the top of the casing 1 and inside thereof, and is encircled within the casing by a spiral spring 4, one end of which 60 spring bears against the shoulder 5 of bow 2 and the other end of which bears against the upper surface of flange 6. Flange 6 is securely attached by screws or rivets to the inner surface of casing 1, and is provided with a circular hole into which one end of bow 2 is inserted. Flange 6 serves both as a pivot for the movement of bow 2, backward and forward and as a means for preventing the movement of spring 4 downward on bow 2. Shoulder 5, which is secured on bow 2, 65 enables the spiral spring 4 to project bow 2 out of casing 1 when the same is unlocked, as well as a means for preventing the bow 2 from being removed entirely from the top 70 of the casing when the padlock is in an unlocked position. Secured loosely to the inside of casing 1, just under the top thereof, by means of screws 11 and 12 is the locking means 7, one end of which is provided with 75 a circular ring 8, which engages in slot 10^a when the device is locked. The other end of locking means 7 is provided with a flat flanged projection 9, which engages with slot 10 in bow 2 when the same is in a locked 80 position. To the central portion of locking means 7 is attached a pin 13 which extends outwardly through slots in tumblers 14. Through the end of pin 13 is inserted a small 85 cotter pin 13^a which holds the tumblers firmly together and against the locking 90 means 7. Screw 12 extends through one end of tumblers 14, and serves as a pivot for their movement when the key is being operated against their inside surfaces. To one 95 end of each of the tumblers 14 is securely attached steel springs 15 which is also securely attached to the projection on casing 1, which said steel springs tend to hold the tumblers downward when the key is not being operated against them. Attached to locking means 7 is one end of spiral wire 100 spring 16, and to the top of casing 1 the other end thereof is attached. The said spring 16 tends at all times to hold the locking means 7 in a locked position, and only by exerting a pulling force thereon by means of the key can the locking means 7 be released from the slots in the bow 2. On the inside of casing 1 and positioned adjoining the bottom thereof, is another locking 105 means 17, each end of which is loosely 110

attached to the inside of casing 1 by means of screws 18 and 19. Screw 19^a extends through one end of tumblers 20, and tends to hold them firmly together as well as 5 against the surface of locking means 17. The said screw 19^a serves also as a pivot around which the said tumblers move when the key is being operated. To the central portion of locking means 17 is attached a 10 pin 21 which extends outwardly through the slots 22 in the center of tumblers 20. Through the end of pin 21 is inserted a small cotter pin 21^a which holds the tumblers firmly together on pin 21. To the end of 15 each of the tumblers 20 is securely attached a steel spring 23 which is also secured to a projection on casing 1, and which tends to hold the tumblers inwardly when the key is not being operated against them. The end 20 of locking means 17, nearest the bow 2 is provided with a projection 24 which fits into slot 25 on the end of bow 2, when in a locked position. To a projection on locking means 17 is attached a spiral wire spring 16, 25 similar to the other spiral wire spring 16, which functions in the same manner in connection with the locking means 17, as does spring 16 function with locking means 7. Through the center of casing 1 is a circular 30 hole through which a circular key block 26 is inserted, and loosely fitted at its circumferential edges so as to provide for a circular motion inside of said casing 7. The said block extends through one side of the 35 casing to the inside surface of the other side thereof, and moves freely therein. Through the center of key block 26, is a slot 27 which extends entirely through the same and into which the key 28 is inserted. Extending 40 through the sides of key block 26 and parallel to the slot 27 are apertures 30 through which the two unlocking means 29 are permitted to project. The key 28 is provided with a hollow handle 31 through which a 45 pin 32 is inserted. One end of pin 32 is provided with a finger piece 33 and the other end thereof is provided with teeth which engage with similar teeth on the inside end of unlocking means 29. Encircling the pin 50 32 is a spiral wire spring 34 which tends to hold the pin 32 upward, by reason of the fact that one end of the said spring bears against the shoulder of the pin 32 while the other end thereof bears against a projection on the inside of handle 31. The two 55 unlocking means 29 are pivoted within the key 28 on pins 35, and are securely held therein by said pins. The padlock casing is made in two sections, one a main structure 60 to which the various screws and securing pins are secured and the other, a cover, which entirely encases the working parts and holds the key block firmly therein.

Having explained the various parts of 65 construction I will now endeavor to explain

the method in which they function in reference to each other.

Assuming that the padlock is in a locked position and that it is desired to be opened, the key 28 is inserted within the slot 27 of key block 26, and the finger piece 33 of said key is pressed toward the lock. As the pin 32 moves inwardly the teeth thereof being engaged with the teeth of the unlocking means 29, the said unlocking means 29 moving on its pivots 35, move to a horizontal position through the apertures 30 of key block 26. While still holding the said finger piece in a downward position, the handle 31 is turned toward the right. As the said handle is turned as aforesaid the key block 26 together with the unlocking means 29 are likewise turned until the extreme ends of said unlocking means 29 come in contact with tumblers 14 and 20. As the said unlocking means 29 continue to move as aforesaid, the said tumblers are pressed outwardly and the said unlocking means 29 are allowed to come in contact with each of the two projections of locking means 7 and 17. 85 By still turning the said handle 31 as aforesaid, the unlocking means 29 force the said locking means 7 and 17 away from the slots 25, 10 and 10^a and allow the spiral spring 4 which presses against shoulder 5, to force the bow 2 upward in an unlocked position as shown in Fig. 6. After the said locking means 7 and 17 have been disengaged from the said slots in bow 2, the key 28 may be removed from the key block 26, by releasing the finger piece 33. As the said finger piece 33 is released, the spiral spring 34 encircling pin 32, forces said pin outwardly and the engaged teeth in unlocking means 29 and at the end of pin 32 are turned until the said unlocking means 29 are inside the key 28, as shown in Fig. 2. When it is desired to lock the device the bow 2 is pressed inwardly until the circular ring 8 of the locking means 7, the flanged projection 9, of said locking means and the flanged projection 24 of locking means 17 come into contact respectively, with the slots 10^a, 10 and 25 of the bow 2. As the said projections and said ring come into contact with the said slots of the bow 2, the spiral springs 16 associated with the locking means 7 and 17, pulling said locking means against the said bow, cause the said projections thereof to become firmly engaged with the slots in the bow 2, thus securely locking the device, and holding it in a locked position.

While I have shown and described the preferred embodiment of my invention, obviously various modifications may be made within the spirit of the appended claim.

I claim:

In a padlock, a casing, a key block extending through said casing, a slot in said key block for the insertion of a key therein,

a pair of apertures in said key block for the emission of a pair of unlocking means of said key, two sets of tumblers for the engagement of said unlocking means therewith, a pair of locking means associated with said tumblers, a bow, the ends of which enter within the said casing, three slots within said bow for engagement with said pair

of locking means, a spring attached to each locking means for pulling it into engagement with said bow, and a spiral spring encircling said bow, for forcing the slots thereof away from said locking means after disengagement therewith.

DELINDO BARTOLACELLI.
